CLAIM

The ornamental design for the compact disc storage rack, as shown and described.

DESCRIPTION

FIG. 1 is a perspective view of a compact disc storage rack showing my new design;

FIG. 2 is a front elevation view thereof;

FIG. 3 is a rear elevation view thereof with a right side elevation and a left side elevation being a mirror image thereof;

FIG. 4 is a top plan view thereof; and,

FIG. 5 is a bottom plan view thereof.

The compact disc receiving apertures have been partially shown in FIG. 1 for convenience of illustration, the appearance thereof being best illustrated in FIGS. 2 and 4. The broken lines of FIG. 1 represent a continuation of the features shown.
